CALCULATING MACHINE

Carl M. F. Friden, Oakland, Calif., assignor to
 Marchant Calculating Machine Company,
 Emeryville, Calif., a corporation of California

Application January 4, 1927, Serial No. 158,892
 Renewed February 5, 1934

31 Claims. (Cl. 235—79)

The invention relates to calculating machines and particularly to calculating machines adapted to perform the operations of addition, subtraction, multiplication and division.

5 An object of the invention is to provide a calculating machine which is automatic in its operation to compute problems involving division.

Another object of the invention is to provide a calculating machine having a quotient register 10 which is constructed and arranged to show the true quotient with means for stopping the actuating means of the calculating mechanism so that when the machine is brought to a stop automatically, the true figure of the quotient appears in 15 the quotient register.

Another object of the invention is to provide a calculating machine with means for reversing the direction of rotation of the actuator, when the machine is employed in solving problems in division, when the figure disc of the quotient register discloses a figure one greater than the true quotient figure.

Another object of the invention is to provide a calculating machine provided with means for automatically reversing the direction of rotation 25 of the actuating means, when performing problems in division and stopping the actuating machine at the end of one cycle of rotation in the reversed direction.

30 Another object of the invention is to provide a calculating machine which, when set to perform problems in division, is controlled by the depression of a key, the depression of the key serving to cause rotation of the actuating means first in one direction and then automatically in the opposite direction, to disclose the true quotient figure.

Another object of the invention is to provide a calculating machine which when set to perform 40 problems in division, is capable of performing a division without shifting the product register and is actuated as follows: Having the dividend entered into the product register with the product register in its unit position, the divisor is then set on the key-board by means of the de- 45 pressible keys; the minus key is then depressed and held depressed, which causes rotation of the main actuator in a subtractive direction. Such subtractive direction is maintained continuously until an over-draft occurs in the product register 50 at which time an automatic reversing mechanism, which is controlled by a registering movement of a numeral wheel, reverses the direction of the main actuator and stops the main actuator upon its first forward movement, thus producing the correct quotient figure in the quotient register.

The invention possesses other advantageous features, some of which with the foregoing, will 55 be set forth at length in the following description,

where I shall outline in full that form of the invention which I have selected for illustration in the drawings accompanying and forming a part of the present specification. In said drawings, I have shown one embodiment of my invention, but it is to be understood that I do not limit myself to such form, since the invention, as set forth in the claims, may be embodied in a plurality of forms.

5 Referring to said drawings:

Figure 1 is a rear elevation of a calculating machine embodying my invention, parts of the structure being omitted to more clearly disclose the features of this invention.

10 Figure 2 is a rear elevation of a calculating machine embodying my invention disclosing other 15 features of the mechanism.

Figure 3 is a longitudinal vertical section through the rear portion of the calculating machine, showing portions of the mechanism which control the automatic reversal of the actuating 20 means.

Figure 4 is a longitudinal vertical section through the rear portion of a calculating machine, showing the reversal control mechanism in 25 operative position.

Figure 5 is a fragmentary view of a portion of the actuating means and several of the numeral wheels of the product register, the parts being in the same position as the corresponding parts in 30 Figure 3.

Figure 6 is a fragmentary view of a portion of the actuating means and a portion of the product register, the parts being in the same position as the corresponding parts in Figure 4.

Figure 7 is a fragmentary view showing the 35 means employed for transmitting motion from the control lever to the slide shown in Figures 3 and 4.

Figure 8 is a vertical longitudinal section through a calculating machine embodying my 40 invention showing the means for controlling the starting and stopping of the actuating means.

Figure 9 is a fragmentary rear elevation of the 45 upper portion of the machine showing the operative means for stopping the actuating means.

Figure 10 is a fragmentary view of one of the elements of the actuating means showing the construction of the tens carrying pin.

Figure 11 is a longitudinal vertical section 50 through the calculating machine showing the means for manually controlling forward and reverse rotations of the actuating means and also the actuating means for the quotient register.

Figure 12 is a vertical section through a portion 55 of the machine showing the tens carrying mechanism associated with the quotient register.

Figure 13 is a horizontal section through the 60 rear portion of the calculating machine showing the driving motor, the clutch, the reversing gear and the means for actuating the reversing gear.

Figure 14 is a vertical section through the clutch and reversing gear.

Figure 15 is a section through the reversing gear taken on the line 15—15 Figure 14.

- 5 The invention relates to motor driven calculating machines and particularly to the control mechanism for controlling the operation of the actuating means. Interposed between the driving motor and the actuating means is a clutch 10 and a reversing gear and the control mechanism is associated with these elements to effect the starting, stopping and reversal of the actuator. A control key is provided, which, when depressed, causes rotation of the actuator in a direction to 15 perform problems in addition and a control key is provided in association with the addition key, so that the rotation of the actuator is limited to one rotation or is permitted to rotate as long as the addition key is held depressed. There is also 20 provided a subtraction key, which when depressed, causes rotation of the actuator in the reverse direction, and this key is also associated with the second control key above mentioned, so that depression of the subtraction key may result 25 in one reverse rotation only of the actuator or may permit the actuator to rotate as long as the subtraction key is held depressed. The subtraction key is also associated with means, for use in solving problems in division, for automatically 30 reversing the direction of rotation of the actuator upon a certain registering movement of the numeral wheels and to stop the actuator at the end of one cycle of such reverse movement, such reverse movement being a forward rotation of 35 the actuator. The calculating machine comprises a rotary actuator and a plurality of keys for introducing values into the actuator. The depression of a key introduces a value corresponding to the numeral on the key, into the rotatable actuator, and rotation of the actuator 40 serves to transfer these values into the counter or register, to effect the calculating operation. The values introduced into the actuator are transmitted, on rotation of the actuator, to the figure discs of the counting mechanism, which, 45 for the purpose of making direct action of the selected values on the figure discs of highest value possible, is disposed in parallel displaceable relation to the axis of the actuator. The 50 present invention does not relate to the construction of the actuator or to the means for introducing the values into the actuator and therefore such part of the calculating machine will not be described herein.
- 55 The present machine includes a suitable frame within which the various instrumentalities of the calculating machine are arranged. These instrumentalities include a rotary reversible actuator 2 comprising a series of units into which values are 60 introduced by the depression of keys. Each unit is also provided with tens carrying pins (Fig. 8) for transferring values to the numeral wheel of the counting mechanism of the next higher order. Each unit is provided with two tens carrying pins 65 and the two series of pins on the actuator are arranged in diverging spirals. One series of pins is effective in carrying tens during a forward rotation of the actuator and the other series of pins is effective in carrying tens during a reverse rotation 70 of the actuator. The values introduced into the actuator by the depression of keys, are transferred, upon rotation of the actuator, in either direction, to the numeral wheels 3 of the counting mechanism, or product register as it is generally known, through the intermediate gears

4 (Fig. 3). The product register, together with its associated intermediate gears and transfer levers, is arranged on a transversely movable carriage 5, which is guided in suitable trackways in the frame, so that the carriage may be moved to establish cooperation between any desired numeral wheel and any desired unit of the actuating means. Associated with each counting wheel 3 is a transfer lever 6 which is actuated upon movement of the numeral wheel forward to or 10 reversely from zero position. This movement of the transfer lever 6 is effected by the associated toothed member 7 secured to the numeral wheel.

The actuator is driven by the motor 8 which is preferably continuously in rotation during the 15 operation of the machine. Interposed between the motor and the actuator is a clutch for connecting and disconnecting the motor from the actuator and a reversing mechanism, whereby the direction of rotation of the actuator may be 20 reversed. The clutch, shown in Figures 11 and 14 embodies a driving shaft 9, suitably connected to the motor shaft and provided on its end with a ratchet pinion 12, which rotates continuously with the motor. Journalled on the driving shaft 9 and enclosing the ratchet pinion 12 is a clutch housing 13 (Fig. 11) within which is pivoted a dog 14 which is adapted to be moved into and out of engagement with the ratchet pinion 12, to connect and disconnect the pinion and the housing. The dog 25 or pawl 14 is urged toward engagement with the pinion 12 by the spring 15. The clutch housing 13 is provided in its periphery with an aperture 16 through which a foot 17 on the end of the pawl 14 extends, when the pawl is in engagement with the pinion. The pawl is disengaged from the pinion by inward movement of the foot 17 and this is accomplished by means of the clutch control lever 18 which is provided on its end with a foot 19 which, when the lever 18 is released of 30 its restraint is moved into contact with the periphery of the housing 13 by the spring 21 and, as the housing rotates, the foot 19, contacts with the foot 17, and enters the aperture 16 thereby 35 disengaging the clutch and locking the clutch housing. The clutch housing is so positioned with respect to the actuator, that when the clutch housing is locked, the actuator is locked in full 40 cycle position. Secured to the clutch housing 13 45 (Fig. 14) is the hollow stub shaft 23 of the reversing gearing. Journalled on the hollow shaft 23 are two gears 24 and 25, either of which may be directly connected to the hollow shaft, to rotate therewith. Each of the gears 24 and 25 is provided on its inner periphery with an interrupted 50 flange 26, the two flanges being in contact. The hollow shaft 23 is provided with an aperture extending diametrically therethrough, and extending through the aperture is a cross pin 27 which is adapted to seat in the interruption in either 55 of the flanges 26. The pin 27 is of less diameter than the depth of the flange so that the pin may seat entirely within either flange. The pin is movable transversely, in the direction of the axis 60 of the shaft 23, to bring it into engagement with either of the gears 24 or 25, and for this purpose, the pin 27 is secured to the rod 28 which extends outward from the end of the hollow shaft 23. The interruptions in the flanges 26 are somewhat 65 wider than the diameter of the pin 27 to permit the pin to be shifted to reverse the direction of rotation of the actuator, without bringing the actuator to a stop. Meshing with the gear 24 70 (Fig. 13) is an idler 31 which in turn meshes with a gear 32 which is directly in mesh with the 75

gear 25. Therefore, the gear 32 is driven in one direction when the gear 24 is in engagement with the hollow shaft 23, and in the opposite direction when the gear 25 is in engagement with the hollow shaft 23. Secured to the shaft of the gear 32 is a gear 33, lying on the opposite side of the intermediate wall 34 and the gear 33 is connected to the gear 36 on the actuator shaft by the intermediate gear 35. Therefore, shifting of the pin 27, reverses the direction of rotation of the actuator.

Means are provided for either manually or automatically shifting the pin 27 to reverse the direction of rotation of the actuator. Engaging a circumferential groove in the outer end of the rod 28 is a fork 38 which is attached at its other end to the shifting rod 39 (Fig. 13) which is suitably journaled within the frame of the machine and which extends through the hollow shaft carrying the transmission gear 41. The fork 38 is held to the rod 39 between the fixed collar 42 and the spring 43 which is in turn held in place by the fixed collar 44. The fork 38 is provided on its end with a collar 45 through which the rod 39 passes and due to the interposition of the spring 43, the fork 38 is movable with respect to the rod 39. The spring 43 is of sufficient strength to cause the fork 38 to move with the rod 39 when the rod 39 is moved, but permits the fork 38 to be otherwise moved to separate the collars 42 and 45. The reversing pin 27 is manually moved by movement of the rod 39, and is automatically moved by movement of the fork 38 independently of the rod 39.

Manual operation of the reversing gear is effected by the depression and release of the minus key 51 which is preferably arranged on the key board of the machine. Pivoted within the machine is a bell crank lever 52 (Fig. 11) which is normally held in restrained position by the spring 53, and when the lever 52 is in such restrained position, the reversing mechanism is in position to cause forward rotation of the actuator. One leg of the bell crank lever 52 underlies a pin 54 on the stem of the minus key 51 so that when the key 51 is depressed, the lever 52 is moved against the restraint of the spring 53. The lever 52 is connected by means of the link 55 with the lever 56 having a sector shaped cam 57 which engages in a slot 58 in the rod 39. Depression of the minus key 51 therefore shifts the rod 39 to cause reverse rotation of the actuator.

The machine is also provided with a plus bar 61, depression of which causes forward rotation of the actuator. The connection between the motor and the actuator is controlled by the clutch, and the action of the clutch is controlled by the lever 18 which is normally held in clutch disengaging position by the spring 21. Means are provided whereby the depression of either key 51 or key 61 will rock the lever 18 to move it out of engagement with the clutch housing 13 and permit engagement of the clutch. Pivoted within the frame of the machine is a bell crank lever 62 having an inclined arm 63 underlying a roller 64 on the stem of the key 51 and having a substantially vertical arm 65 lying in front of a roller 66 carried by the frame 67 of the plus bar 61. The frame 67 is mounted on links 68 in such manner, that depression of the plus bar 61 causes forward movement of the roller 66 against the upright portion 65 of the bell crank lever thereby rocking said lever. It will be seen from Figure 11, therefore, that depression of either key 51 or 61, will cause clockwise rotation of the

bell crank lever 62. Pivoted to the upper end of the arm 65 of the lever 62 is a bar 71 provided on its under side at its rear end with a notch 72 in which a pin 73 on the forward end of the clutch control lever 18 is normally disposed. Therefore, rearward movement of the bar 71 rocks the lever 18 about its pivot to move it out of engagement with the clutch housing. Release of either of the depressed keys 51 or 61 will cause the clutch lever 18 to again move into engagement with the clutch housing, and other means are provided, independent of the depressed position of the keys 51 and 61 for releasing the lever 18 to cause it to engage the clutch housing. This is accomplished by raising the rear end of the bar 71 to move the notch 72 from engagement with the pin 73 as will be described hereinafter.

The calculating machine is also provided with a register or counting mechanism, usually known as the multiplier register or quotient register for indicating directly the proper and correct multiplier or quotient. This register comprises a series of numeral wheels 75 (Fig. 11), each numeral wheel being provided with an intermediate gear 76 and a transfer lever 77. Means are provided for causing a single operation of a selected numeral wheel for each rotation of the actuator in either direction, and tens carrying means are provided so that the register will always show the correct figure. The numeral wheels 75 are actuated in time with the rotation of the actuator, by the rotatable single toothed member 78 which is splined to the shaft 79 which is rotatable in time with the actuator. The tens carrying device in the particular embodiment shown, (Figs. 2 and 12) comprises a drum 81 having two series 82 and 83 of tens carrying pins thereon, the pins in the two series being arranged in diverging spirals so that they are reversibly operative upon reverse rotation of the drum. The drum is secured to a shaft 84 journaled in the frame of the machine and the tens carrying pins 82 and 83 cooperate with the transfer levers 77 to transfer values to the numeral wheels of the next highest order. Splined to the shaft 84 is a gear 85 which is provided with a collar 86 which is engaged by a fork 87 so that the gear 85 may be moved longitudinally of the shaft. The gear 85 is coaxial with respect to the gear 35 and is movable axially into mesh with either the gear 31 or 32. Therefore, the direction of rotation of the drum 81 may be reversed with respect to the direction of rotation of the actuator. Secured to the opposite end of the drum shaft 84 is a gear 88 which is connected, through the intermediate gear 89 with the gear 91 secured to the end of the multiplier register actuating shaft 79. Therefore, the direction of rotation of the actuating member 78 is reversed simultaneously with the direction of rotation of the drum 81. The actuating member 78, is adjustable longitudinally of its shaft so that it is disposed in cooperative relation with the selected numeral wheel 75 and for this purpose, the gear is provided with a grooved collar which is engaged by a shifting fork 92 which is medately connected to the carriage 5, as shown in my copending application, Serial Number 539,422 filed February 27, 1922 so that the member 79 is shifted longitudinally in a direction opposite to that of the direction of movement of the carriage.

In performing operations of division, the direction of rotation of the member 78 and the drum 81 are reversed with respect to the direction of rotation of the actuator, and means are

provided for effecting this reversal of direction of rotation. The shifting fork 87, Figure 2, is secured to a shifting rod 94 which is suitably supported in the frame of the machine. The 5 rod is provided on one end with a slot and extending into this slot is the cam sector 95 forming part of the shifting lever 96, the upper end of which extends through an aperture in the casing of the machine. When it is desired to 10 perform problems in division, the shifting lever 96 is moved to its backward position as shown in Figures 2 and 8, thereby shifting the gear 85 to cause a reverse direction of rotation of the actuating and tens carrying means associated 15 with the quotient register. A spring pressed ball 97 is provided for holding the rod 94 in either of its shifted positions. Means are provided for preventing this rod from being shifted when the mechanism is out of full cycle position, this 20 means comprising a disc 98 secured to the shaft 84 and having a notch 99 therein which, when the mechanism is in full cycle position lies in the path of the finger 101 secured to the rod 94. This finger, on shifting of the rod from one 25 position to another moves from one side of the disc 98 to the other side and, is movable only when the notch 99 is disposed in its path of movement.

In machines of this character when used in 30 the performance of problems in division, the numeral wheels of the product register, to the left of the wheels being operated upon by the actuator, change sign when an endeavor is made to divide the divisor into the dividend a greater 35 whole number of times than is possible. Under such conditions, what is known in the art as a "transitional carry" takes place and the numeral wheel registration changes from a positive to a negative registration or from a negative to a 40 positive registration. Heretofore, this transitional carry has been utilized either to sound a signal to indicate that the division had proceeded too far or to throw into operation mechanism for stopping the machine. Division is accomplished by a reverse rotation of the actuator and, when a condition of over-division existed 45 the actuator was then rotated in a forward direction to correct the over-division condition. When the machine was provided with means for 50 stopping the actuator at the end of the first cycle of rotation of over-division, the machine was then manually operated to cause a single forward rotation of the actuator, thus producing the proper number in the product register, 55 and the proper indication in the quotient register. In the present construction the transitional carry is utilized to effect the automatic reversal of the direction of rotation of the actuator, without stopping the actuator, so that the actuator 60 is then given a forward rotation and is brought to a stop at the end of the first cycle of forward rotation. Therefore, in performing problems in division with a machine embodying the present invention, the operator merely holds the minus 65 key 51 depressed until the machine comes to a stop, at which time, the quotient register shows the correct figure. While the key 51 is held depressed the actuator rotates in a reverse direction until there is a change of sign of the registration in the product register and then the 70 actuator is automatically reversed and stops at the end of the first cycle of forward rotation.

Means are provided which are operative during the reverse rotation of the actuator for reversing or changing to a forward rotation of

the actuator when the numeral wheel of the next to the highest order within the range of the actuator changes signs. The numeral wheel of highest order is that numeral wheel which is so positioned that it is actuated by the transfer pin on the highest order actuator unit when a transfer is determined. Consequently the numeral wheel of next to highest order is that one which is positioned intermediate the two highest actuator units. The first change of sign of the 10 numeral wheel of next to highest order in a division operation is from zero to 9. On this change of sign, the toothed element 7 (see Figures 3 and 4) moves the transfer lever 6 backward from the position shown in Figure 3 to the 15 position shown in Figure 4. During the operation of division, the actuator rotates in a counter clockwise direction as indicated by the arrow. Each unit of the actuator is provided with two tens carrying pins 112 and 113, the pin 112 functioning during a reverse rotation of the actuator and the pin 113 functioning during a forward rotation of the actuator. In Figures 3 and 4 the actuator unit at the left hand end of the actuator is shown, and on this unit, the two pins 112 and 113 are fairly close together, but on the successive units, they are spaced apart a greater distance, so that the two series of pins lie in diverging spirals. The transfer lever is provided on its rear end with a lip 114 which extends beyond the periphery of the actuator unit, when the transfer lever is in the transferring position shown in Figure 4. The actuator unit is provided with a restoring cam 115 having its high portion positioned between the pins 112 and 113, so that after one pin has functioned in moving over the transfer lever, the transfer lever is restored to the position shown in Figure 3, before the next transfer pin comes to the transfer lever. The transfer lever is provided on its rear portion with a transverse cam 116 which, as the first transfer pin rides over the cam, causes a lateral or transverse movement of the transfer pin into the path of the intermediate gear 4 of the counting wheel of the next higher order. In the present construction, this lateral or transverse movement of the transfer pin 112 which is associated with the numeral wheel of the next to the highest order is used to control the automatic reversal of the direction of rotation of the actuator. 30 35 40 45 50 55 60 65 70 75

Pivoted on a diametric axis at right angles to the center line of the transfer pin 112, on the actuating unit at the left of the actuator is an oscillating lever 117 which in the present construction is provided with an aperture through which the shaft of the actuator extends. The lever 117 is rotated with the actuator and is normally held in the position shown in Figure 5, by the spring 118, interposed between the lever and the actuator. The transfer pin 112 which is normally held in retracted position by the spring 119 (Figure 10) is provided on its side adjacent the oscillating lever 117 with a projection 121 against which the end of the oscillating lever 117 bears. As the transfer pin 112 is moved transversely by running over the cam 116 on the transfer lever, it imparts its movement to the oscillating lever 117, moving it to the position shown in Figure 6.

Pivoted within the machine and disposed behind the last actuator unit to the left is a lever 122 which is normally held in retracted position by the spring 123. The upper end of this lever 122 is disposed within the periphery of the actuator unit and is normally out of the path of the

rear end 124 of the oscillating lever 117. When the lever 117 is in the position shown in Figure 5, the lever 117 passes, without operating the lever 122, upon reverse rotation of the actuator. 5 When, however, the lever 117 is moved into the position shown in Figure 6, by the transfer pin 112, the rear end of the lever 124 contacts with the upper end of the lever 122 and rocks the latter lever. This rocking movement is instantaneous and occurs only while the transfer pin 112 is traveling over the cam 116 of the transfer lever since, when the lever 117 is restored to normal position by the spring 118, the end of the lever 117 is moved transversely out of contact with the lever 122. When the actuator is in the position shown in Figure 3, the actuator is in full cycle position and consequently, it follows that the lever 122 is oscillated immediately before the actuator reaches full cycle position.

20 The lever 122 is provided on its lower end with a wedge shaped projection 126 (Figure 7) which extends through an aperture in a fixed plate 127 into an aperture in the slide 128. Movement of the lever 122 therefore causes instantaneous sliding movement of the slide 128. The slide 128 is connected at its other end with a lever 129 which is provided on its other end with a tooth 131 which is in contact with the shifting fork 38. Problems in division are performed by depression 30 of the minus key 51 and when this key is depressed, the shifting fork 38 is shifted to the position shown in Figure 13. Operation of the lever 122 causes movement of the shifting fork against the pressure of the spring 43, moving the transverse pin 27 into engagement with the collar 26 on the gear 25, thereby reversing the direction of rotation of the machine. The actuation of the lever 122, occurs at full cycle position of the actuator and at such position, the interruption in 35 the two contacting flanges 26 on the gears 24 and 25 respectively, are in alignment, so that the pin 27 may be shifted from engagement with the gear 24 to engagement with the gear 25. Therefore, it is seen that upon a change of sign of the 40 numeral wheel of the order next to the highest within the range of the actuator, when the actuator is rotating in a direction to perform a problem in division, that the direction of rotation of the actuator is instantaneously reversed 45 to a forward direction of rotation. During this operation, the clutch is not disengaged so that the machine is not stopped but continues its rotations, the only change being an automatic reversal of the direction of rotation of the actuator. This is accomplished without the intervention of the operator of the machine.

I shall now describe the mechanism which I employ for stopping the actuator in full cycle position at the end of the first cycle of reversed 50 or forward rotation of the actuator. This mechanism is effective to release the control bar 71 from the clutch lever 18, thereby permitting the spring 21 to return the clutch lever 18 to normal position and thereby disengage the clutch and 55 stop the clutch housing. In the present instance, this is effected by quickly raising the clutch bar 71 to move the recess 72 from contact with the pin 73, thereby removing the restraining element from the clutch lever and permitting the spring 60 21 to move said lever. The particular mechanism employed for this purpose comprises a lever 65 135 (Fig. 2), fulcrumed on a fixed portion of the machine and having its end 136 extending through an aperture 137 in the control bar 71. Upward movement of the end 136 of the lever will disen-

gage the control bar 71 from the clutch control lever 18.

The lever 135 comprises part of a lever system consisting of the levers 135 and 138, which are connected together at their adjacent ends. The lever 138 is also fulcrumed on a fixed portion of the machine, and due to its connection with the lever 135, the two levers move simultaneously. Upward movement of the outer end of the lever 138 will be accompanied by an upward movement of the end 136 of the lever 135, and means are provided for moving the lever 138 at the proper time to cause the lever 135 to operate to release the clutch control lever 18.

The actuator comprises a series of actuator units for transferring values set up therein to the counting wheels of the product register. These actuator units are fully disclosed in my United States Patent Number 1,524,924 of February 3, 1925. The present machine is provided with an actuator having nine of these actuating units and is provided at the left of the actuating units with four over-flow actuating units, these overflow units comprising discs carrying tens carrying pins for the operation of the tens carrying mechanism. One of these tens carrying units 2a, (Fig. 1) preferably the next to the last unit at the left end of the actuator, as viewed from the front of the machine, is chosen to operate the automatic stop mechanism. The actuator unit 2a is provided adjacent its periphery with a laterally extending pin or abutment 142. Arranged within the machine and mounted therein for universal movement is an operating lever 144 (Fig. 8) which is provided on its upper end with a tooth 145, which, when the actuator is in full cycle position, lies below the pin 142 but to one side thereof, so that normally, the tooth 145 of the lever is not engaged by the pin 142, upon rotation of the actuator. This is the normal inoperative position of the lever 144, when the machine is being used for performing problems in division. The lever 144 is fulcrumed on a stud 146 and is held so that the tooth 145 thereon lies to one side of the pin 142 by the spring 147, the lever 144 therefore has a movement of oscillation in a plane perpendicular to the axis of the stud 146 and also has a movement of oscillation in a plane parallel to the axis of the stud 146, so that the lever 144 has a restrained, limited universal movement. The tooth 145 on the upper end of the lever normally lies to one side of the path of the pin 142 and means are provided for moving the lever 144 sidewise to bring the tooth 145 into the path of the pin, when the numeral wheel 3 of the third to the highest order passes from a negative to a positive registration, that is, from 9 to zero. The numeral wheel of the third to highest order is that numeral wheel which is so positioned as to control, through its associated transfer lever 6, the movement of the transfer pins 112 and 113 mounted on the next to the last actuator unit from the right as viewed in Figure 1. Associated with each numeral wheel is a tens carrying lever 6 which cooperates with the tens carrying pins 112 and 113 on the actuator to effect movement of the numeral wheel of the next higher order. On the first reversed or forward cycle of rotation of the actuator, the numeral wheel to the left (Figure 1) of the value selecting actuator unit 2a moves from 9 to zero, changing its sign character and causing movement of the associated transfer lever 6, and such movement is employed to control the operation of the mechanism for automatically stopping the machine in full cycle position. Arranged on the

back of each transfer lever 6 which may be associated with the highest order actuator unit (this being the unit shown in Figures 3 and 4) is a boss 154 and lying in contact with the boss is the laterally extended end 155 of the lever 156. The boss 154 is used for the purpose of taking the wear which might occur at this point and the extended end 155 of the lever 156 is used to insure contact of the boss with the lever. The lever end 155 10 does not extend laterally into position behind the transfer lever of the numeral wheel of the next lower order and is operated only by movement of the transfer lever associated with the actuator unit of the next to highest order. The end 155 of 15 the lever 156 is held in contact with the boss 154 by the flat spring 157 rigidly secured to the lever 156 and bearing at its lower end against a convenient part of the machine; and consequently movement of the tens carrying lever 6 is accompanied by oscillation of the control lever 156.

The operating lever 144 is provided on its side with a cam 158 and the lever 156 normally lies immediately above the inclined surface of the cam (Fig. 2). When the lever 156 is rocked on its fulcrum, it moves over the inclined surface of the cam 158, rocking the lever 144 sidewise and bringing the end 145 thereof into the path of the pin 142 so that the end 145 of the lever is struck by the pin, causing the lever 144 to rock on its pivot. 20 During this reversed or forward rotation, the actuator rotates in a clockwise direction so that the pin 142 strikes the projection 145 on the lever just before the actuator reaches full cycle position, providing sufficient time for the associated mechanism to operate to stop the actuator in full cycle position. The lower end of the lever 144 is in contact with the under surface of the lever 138 so that as the end 145 of the lever 144 is struck by the pin and rocked about the axis of the stud 146, 30 the lever 138 and consequently the lever 135 is rocked on its pivot raising the clutch control bar 71 and releasing the clutch lever 18, which then drops into engagement with the clutch housing, disengaging the clutch and stopping the clutch 35 housing in full cycle position. This stops the actuator in full cycle position with the end 145 of the lever 144 positioned in its normal position below the pin 142, as shown in Figure 8, but to one side of the path thereof, due to the return of the 40 tens carrying lever 6 to its forward position as shown in Figure 8. This automatic stopping means is operative only on forward rotation of the actuator, since on reverse rotation of the actuator, the pin 142 will have moved past the 45 end 145 of the lever 144 before the numeral wheel 3 is moved by the actuator to cause backward movement of the transfer lever.

Means are provided for moving the automatic stop lever 144 to inoperative position when desired. Secured to the shift rod 94 (Figure 2) which is shifted by movement of the lever 96, is a rod 161, which is moved longitudinally with the shifting rod and this rod 161 extends to and engages the lever 144 for the purpose of rocking 60 such lever sidewise on its pivot. The end of the rod 161 passes around the lever 144 below the cam 158, sufficient clearance being provided to permit the lever to be rocked by the pin 142. The actuator unit 2a which carries the pin 142 is 65 provided with an aperture 162 which is transversely aligned with the projection 145 on the lever 144, when the actuator is in full cycle position, to permit the projection 145 to be moved to the opposite side of the actuator unit. Therefore, as 70 the shift lever 96 is moved to its forward position,

the lever 144 is rocked sidewise to bring the projection 145 thereon to the side of the actuator unit remote from the pin 142, so that on rotation of the actuator unit, the pin cannot contact with the automatic stop lever 144.

It is thus seen that in this machine when the sign of the numeral wheels at the left of the register change from zero to 9, that such change of sign causes the operation of automatic mechanism for reversing the direction of rotation of the actuator, that is changing its direction of rotation from a reverse rotation to a forward rotation. During the first cycle of such forward rotation, the numeral wheels at the left of the register again change sign from 9 to zero and such change of sign causes the operation of a control lever which moves an actuating lever into position to be moved by the actuator to stop the machine in full cycle position at the end of the first cycle of forward rotation. In performing 20 problems in division, the operator first enters the dividend into the register arranged on the carriage which is usually termed the product register. The keyboard is then cleared and the divisor is then entered therein. The quotient register is 25 cleared and the minus key is depressed and held depressed until the machine comes to a stop, at which time the correct figure is shown in the quotient register. The machine is not stopped at the time of over-registration in the quotient register but continues to operate, reversing its direction of rotation and coming to a stop only when the proper figure is shown in the quotient register. 30

It should be noted that the capacity of the product register must exceed the capacity of the actuator by one order so that with the register carriage in its extreme left hand position, as viewed in Figure 1, numeral wheels and their associated transfer levers will at all times be in cooperative relation with the two highest actuator 40 units.

I claim:

1. In a calculating machine, reversible numeral wheels, actuating means therefor having a reversible cycle of operation, means controlled by 45 movement of the numeral wheel of next to highest order from zero to 9 for reversing the direction of movement of the actuating means and means controlled by the subsequent movement of the numeral wheel of the third to highest order from 9 to zero for stopping the actuating means.

2. In a calculating machine, reversible numeral wheels, actuating means therefor having a reversible cycle of operation, an operating device for the actuating means, means operative in time with the movement of the numeral wheel of the next to highest order from zero to 9 for reversing the direction of movement of the actuating means and means operative in time with the resultant movement of the third to the highest order numeral wheel from 9 to zero, for stopping the actuating means.

3. In a calculating machine, reversible numeral wheels, actuating means therefor having a reversible cycle of operation, and means operative 65 only during subtractive movement of the actuating means and controlled by the movement of the numeral wheel of next to the highest order from zero to 9, for reversing the direction of movement of the actuating means.

4. In a calculating machine, reversible numeral wheels, actuating means therefor having a reversible cycle of operation, an operating device for the actuating means, a clutch between the operating device and the actuating means, revers-

ible gearing between the operating device and the actuating means, and means operative in time with the movement of the numeral wheel of the next to the highest order from zero to 9 to 5 actuate the reversing gearing to reverse the direction of movement of the actuating means while the clutch is maintained in engagement.

5. In a calculating machine, reversible numeral wheels actuating means therefor having a reversible cycle of operation, an operating device for the actuating means, a clutch and reversing gearing between the operating device and the actuating means, means for causing engagement of the clutch, means operative in time with the movement of the numeral wheel of the next to the highest order from zero to 9 for actuating the reversing gearing to reverse the direction of movement of the actuating means and means controlled by the movement of the third to the highest order numeral wheel from 9 to zero for disengaging the clutch.

6. In a calculating machine, reversible numeral wheels, actuating means therefor having a reversible cycle of operation, an operating device for the actuating means, a control key, means operative by the depression of the control key for causing the operating device to drive the actuating means in a reverse direction and means operative in time with the movement of the numeral wheel of the next to highest order from zero to 9 for causing movement of the actuating means in a forward direction.

7. In a calculating machine, reversible numeral wheels, actuating means therefor having a reversible cycle of operation, means operative during reverse movement of the actuating means and in time with the movement of the numeral wheel of the next to the highest order from zero to 9 to reverse the direction of movement of the actuating means to forward movement and means operative during forward movement of the actuating means and controlled by movement of the numeral wheel of third to highest order from 9 to zero for stopping the actuating means.

45 8. In a calculating machine, reversible numeral wheels, actuating means therefor having a reversible cycle of operation, an operating device for the actuating means, a clutch interposed between the operating device and the actuating means, a control key which when held depressed maintains the clutch in engagement, means operative in time with the movement of the numeral wheel of the next to the highest order from zero to 9 for reversing the direction of movement 50 of the actuating means and control means operative by a registering movement of the third to the highest order numeral wheel from 9 to 0 for disengaging the clutch and stopping the actuator while said key is held depressed.

60 9. In a calculating machine, reversible numeral wheels, actuating means therefor having a reversible cycle of operation, a minus key which when held depressed causes continuous rotation of the actuating means in the subtraction direction and means controlled by a registering movement of the numeral wheel of the next to highest order for reversing the direction of rotation of the actuating means while said key is held depressed.

70 10. In a calculating machine, reversible numeral wheels, actuating means therefor having a reversible cycle of operation, a minus key which when held depressed causes continuous rotation of the actuating means in a subtraction direction, means controlled by a registering move-

ment of the numeral wheel of the next to highest order for reversing the direction of rotation of the actuating means while said key is held depressed and means operated by the reverse rotation of the actuating means for stopping the actuating means.

5 11. In a calculating machine, reversible numeral wheels, actuating means therefor having a reversible cycle of operation, tens carrying elements associated with said numeral wheels, means controlled by one of said tens carrying elements for reversing the direction of rotation of the actuating means and means controlled by one of said tens carrying elements independently of the carriage position for stopping the actuating means.

10 12. In a calculating machine, reversible numeral wheels, actuating means therefor having a reversible cycle of operation, carry mechanism associated with said numeral wheels, means for reversing the direction of rotation of the actuating means upon passage of the next to the highest order numeral wheel reversely from zero position and means for stopping the actuating means upon the resultant passage of the third to the highest order numeral wheel forwardly to zero position.

15 13. In a calculating machine, reversible numeral wheels, actuating means therefor having a reversible cycle of operation, a motor, a normally disengaged locked clutch between the motor and the actuating means, reversing gearing between the motor and the actuating means, a control key, means operative by the depression of the control key for unlocking and engaging the clutch and shifting the reverse gearing to cause reverse rotation of the actuating means, devices operable upon passage of the next to the highest order numeral wheel reversely from zero position for shifting the reverse gear to cause forward rotation of the actuating means 20 and devices operable upon the subsequent passage of the third to the highest order numeral wheel forwardly to zero position to disengage and lock the clutch.

30 14. In a calculating machine, reversible numeral wheels, actuating means therefor having a reversible cycle of operation, an oscillating member carried by and rotating with the actuating means, means operable by said member on reverse rotation of the actuating means for reversing the direction of rotation of the actuating means and means operable upon passage of the next to the highest order numeral wheel reversely from zero position for moving said oscillating member to operative position.

35 15. In a calculating machine, reversible numeral wheels, actuating means therefor having a reversible cycle of operation, a transfer lever associated with the next to the highest order numeral wheel, a tens carrying pin associated with the actuating means for the highest order numeral wheel and means operative by movement of said pin caused by contact with said lever, for reversing the direction of rotation of the actuating means.

40 16. In a calculating machine, reversible numeral wheels, tens carrying elements associated with said numeral wheels, actuating means for said wheels having a reversible cycle of operation, means for rotating said actuating means, reversing gearing between said actuating means and rotating means and control means for said reversing gearing carried by said actuating means and associated with the tens carrying element 45

- cooperating with the next to the highest order numeral wheel.
17. In a calculating machine, reversible numeral wheels, actuating means therefor having a reversible cycle of operation, means for rotating the actuating means, a clutch interposed between the rotating means and the actuating means, reversing gearing interposed between the rotating means and the actuating means, a key manually depressible to position the gearing to cause reverse rotation of the actuating means and to cause engagement of the clutch and manually releasable to cause disengagement of the clutch, means operated by registering movement of a numeral wheel on reverse rotation of the actuating means for shifting the reversing gearing to cause forward rotation of the actuating means and means operative during the first cycle of forward rotation for disengaging the clutch.
18. In a calculating machine, reversible numeral wheels, actuating means therefor having a reversible cycle of operation, transfer levers associated with said numeral wheels means controlled by the transfer lever associated with the next to the highest order numeral wheel during reverse rotation of the actuating means for changing the direction of rotation thereof and means controlled by the transfer lever associated with the next to the highest order actuator unit for stopping the actuating means at the end of the first cycle of the resultant forward rotation of the actuating means.
19. In a calculating machine, reversible numeral wheels, a reversible, rotary actuator therefor, means for initiating one or more cycles of reversed operation of the actuator in the performance of calculations, automatically operating control means for reversing the cycle of operation of the actuator in a direction opposite to the cycle of operation caused by said initiating means, means for stopping the actuator in full cycle position, including settable control means for said stopping means arranged to be actuated during the first cycle of said reversed operation of the actuator.
20. In a motor driven calculating machine, numeral wheels, an actuator therefor having a reversible cycle of operation, means operable in the calculation of problems in division for reversing the direction of movement of the actuator by movement of the numeral wheels in an overdraft registration and means for locking the actuator in full cycle position at the end of the first cycle of reversed movement.
21. In a calculating machine, numeral wheels, a reversible rotary actuator therefor, driving means including a motor, a manually operable drive controlling member freely retractable upon release, means operable in the calculation of problems in division for reversing the direction of rotation of the actuator by movement of the numeral wheels in an overdraft registration, means for stopping the actuator in full cycle position at the end of the first cycle of reversed rotation while said controlling member is manually held and means operable on the release and actuation of the controlling member to hold the stopping means in inactive position.
22. In a calculating machine, numeral wheels, actuating means therefor having a reversible cycle of operation, an operating device for the actuating means, a reversing transmission between said operating device and said actuating means, and means controlled by movement of the
- numeral wheel of next to highest order in an overdraft registration for controlling said reversing transmission.
23. In a calculating machine, rotatable actuating mechanism, reversing mechanism normally biased to transmit drive in one direction to the registering mechanism therefrom, means for biasing said mechanism to transmit drive in the opposite direction, and means for superseding said second biasing means.
24. In a calculating machine, rotatable actuating mechanism, reversing mechanism normally biased to transmit drive in one direction to the registering mechanism therefrom, means for biasing said mechanism to transmit drive in the opposite direction, normally disabled means for superseding said second biasing means, and means for enabling said means concurrently with said second biasing means.
25. In a motor driven calculating machine numeral wheels, an actuator therefor, means for reversing the direction of drive of said numeral wheels, means for biasing said reversing means to subtractive position, and means controlled by said numeral wheels for superseding said biasing means.
26. In a calculating machine, reversible numeral wheels, actuating means therefor, means operable in response to a transitional carry for reversing the direction of operation of said numeral wheels by said actuating means, and other means operable in response to a second transitional carry for stopping said actuating means.
27. In a calculating machine, reversible numeral wheels, actuating means therefor, means controlled by movement of the numeral wheel of the next to the highest order from zero to nine for reversing the direction of operation of said numeral wheels by said actuating means, and other means operable in response to a transitional carry for stopping said actuating means.
28. In a calculating machine, reversible numeral wheels, actuating means therefor, an operating device for the actuating means, a control key, means operative by the depression of the control key for causing the operating device to drive the numeral wheels subtractively, and means operative in time with movement of the numeral wheel of the next to highest order from zero to nine, for causing the operating device to drive the numeral wheels additively.
29. In a calculating machine, reversible numeral wheels, actuating means therefor, an operating device for the actuating means, a control key, means operative by the depression of the control key for causing the operating device to drive the numeral wheels subtractively, and means operative in time with movement of a numeral wheel below the highest order from zero to nine, for causing the operating device to drive the numeral wheels additively.
30. In a calculating machine, reversible numeral wheels, actuating means therefor, and means controlled by movement of the numeral wheel of the next to the highest order from zero to nine for reversing the direction of operation of said numeral wheels by said actuating means.
31. In a calculating machine, reversible numeral wheels, actuating means therefor, and means controlled by movement of a numeral wheel below the highest order from zero to nine for reversing the direction of operation of said numeral wheels by said actuating means.

CARL M. F. FRIDEN.
